UNITED STATES PATENT OFFICE.

WILHELM GOERT BOONZAIER, OF NEW WANDSWORTH, LONDON, ENGLAND.

CIGARETTE-MAKING DEVICE.

Application filed November 22, 1920. Serial No. 425,688.

To all whom it may concern:

Be it known that I, WILHELM GOERT BOONZAIER, a subject of the King of Great Britain, residing at 11 Bramfield Road, 5 New Wandsworth, London, S. W. 11, England, have invented certain new and useful Improvements in Cigarette-Making Devices, of which the following is a specification.

This invention relates to an improved 10 device for making cigarettes and refers more particularly to a simple cigarette maker that may be carried in the user's pocket or tobacco pouch.

The object of this invention is a device 15 of the kind described with which a perfect cigarette may be made in a few seconds with the minimum of trouble and without wasting tobacco, and which device can be manufactured cheaply and be of lasting service.

According to this invention, the cigarette 20 maker comprises two separable semi-cylindrical members forming half tubes each half tube having at one end a guide block or member providing a semi-circular slot 25 adapted to receive the end of the other half tube to secure the two half tubes together to form a complete tube closed at both ends. For example each part may be composed of a longitudinal half-section of a tube having 30 a block or plate fixed in or forming part of one of its ends and having its other end or point suitably pointed and rounded so that the point of one part may enter easily into a slot or loop formed in or over the block 35 or plate at the end of the other part, which said loop is preferably formed by arranging a strap or collar freely over the said block and securing it to the underside of the said tube, the diameter of the said 40 block being equal to the internal diameter of the said tube.

Or the said half tubes may be stamped and pressed, the said stamping having integral therewith at one end a lug with a semi- 45 circular slot or recess representing respectively the said block and loop or slot, which said slotted lug may be turned over in pressing to form a substitute for the said block and loop with equally satisfactory results 50 and at less cost.

It is preferred to make the one said part or half tube slightly longer than its mate.

To make a cigarette a charge of tobacco is placed in one of the members, then the 55 other member is placed over it and the point of one member inserted in the corresponding

slot in the block or end of the other member, whereby the two half tubes are clamped together, these said points being held in opposite directions. The two half tubes are 60 then pressed into the said slots or loops at each end, and any tobacco protruding along the junction edges of the said tubes is cut off by rolling the tube between the fingers whereby the sharp edges of the half tubes sever 65 the projecting threads of tobacco, or the latter is simply scraped off by the nail into the pouch.

The said points being thus secured in the 70 said loops, a complete tube is now formed between the said straps or collars, which tube is fully charged with tobacco and of a length equal to or slightly in excess of that of a cigarette paper which is now wrapped and gummed round the tube, after which 75 the half tubes are taken by their collars and drawn asunder, the empty one being first withdrawn, and the completed perfectly made cigarette can then be removed from the other member. 80

The invention will now be explained with 85 reference to the accompanying drawings, which show several examples of cigarette making tubes according to this invention.

Figure 1 shows the two half tubes, with a charge of tobacco in one of the tubes, the point of which is shown as being just inserted in the slot of the other tube.

Figure 2 is a section on the line *a*—*b* of Figure 1, and Figure 5 is a section on the 90 line *c*—*d* of Figure 1.

Figure 4 shows the two half tubes secured together, and the tobacco charge slightly compressed longitudinally, Figure 5 being a 95 section on the line *e*—*f* of Figure 4.

Figure 6 shows the stop end of part of a half tube, formed by stamping, and Figure 7 shows the end turned up into position.

Figure 8 shows a modified form of stamping and Figure 9 part of a half tube formed from such stamping. Figure 10 shows a modified form of half tubes, and Figure 11 shows the two half tubes about to be secured together. 100

Figure 12 shows this form of cigarette maker assembled with a charge of tobacco in the tube, and a cigarette paper wrapped around the outside of the tube.

Figure 13 shows a modified form of stop 110 or cap for one end of this cigarette maker.

Referring first to Figures 1 to 5, the con-

2

struction of my invention therein illustrated, as will be seen, consists substantially of two separate half tubes, 1, 2, each having at one of its ends a small cylindrical block or plug 3, and a surrounding circular collar 4, the collar, plug and tube being secured together by rivets 5 (Figure 4). As the part 1 (or 2) is only semi-circular in cross section, a semi-circular slot or space 6 will be formed 10 between the plug 3 and the inner surface of the collar 4, when the latter is fitted in position over the half tube and plug, as shown particularly in Figures 2 and 3. This slot corresponds in shape and size to 15 the half tube 1 (or 2) and is provided to receive the free end thereof. For the purpose of facilitating the entry of the ends of the half tubes into the slots, these ends are preferably rounded off or pointed as 20 shown in the drawings. One or both of the plugs may be provided with a knob 3a.

To make a cigarette, one of the half tubes is charged with tobacco, which is pressed firmly into the channel as shown in Figure 25 1. The other half tube is then placed, inverted, over the charged half tube, and the point of the latter is inserted into the slot 6 of the former. The point of the upper half tube is then brought into line with the slot of the under half tube, and the two parts are then pressed together (Figure 30 4). The charge of tobacco is thus compacted both circumferentially and also at its ends. A sheet of cigarette paper 7 is 35 then wrapped round the tube formed by the two half tubes, and its edge moistened and pressed down. The empty half tube is then withdrawn longitudinally, leaving the tobacco charge between the half tube 40 2 and the upper part of the cigarette paper tube. The paper tube and its tobacco charge is then slid off the half tube 2, and the cigarette is complete.

In order to cause the tobacco charge to 45 fill but not to unduly project from the ends of the paper tube, it is preferable, before the cigarette paper is wrapped round the two half tubes, to compress the charge longitudinally to a length somewhat less than 50 the length of the cigarette desired, as the charge expands somewhat longitudinally when the half tubes are removed.

In the modification shown in Figures 6 and 7 each half and its block or end is 55 formed from a single stamping, the end 2a being bent up at a right angle (Figure 7) and soldered, if necessary. The slot 6 formed in this end piece receives the end of the other half tube.

In the construction shown in Figures 8 and 9, the body 2 is bent into a semi-circular channel and the extension 2b is folded over to form, with the end of 2, a complete tube (Figure 9) and the flap 2a is folded inwards 60 to constitute a block or closure for the chan-

nel. As this flap 2a is connected to the extension 2b by means of a neck 2c, the slot 6 is in two halves, and the end of the half tube 1 must therefore be forked to enable it to pass into the slot 6.

In the modification shown in Figures 10 to 12 there is only one fixed block or end 3, the other end being in the form of a removable cap 8. The block 3, which is pinned or otherwise secured in the end of the channel member 2 has a central bore 3b. The other channel member 1 is provided with a corresponding end having a projecting pin 3c, adapted to engage in the bore 3b as shown in Figure 11. To secure the other ends of the two half tubes 1, 2, together when placed one over the other, I employ a cap 8, consisting of a cylindrical cup having a cylindrical block or plug secured therein of such diameter as to leave a circular slot or passage between the circumference of the block and the inner surface of the cup. When the two half tubes are engaged together, after charging the tobacco, the cap is fitted over the ends of the half tubes 1, 2 and holds them securely in place. A sheet of cigarette paper is then wrapped round the tube, the cap removed, one of the half tubes withdrawn and the formed cigarette then removed from the outer half tube. The cap 8 is preferably secured to its half tube by means of a light chain 9.

Figure 13 shows a modified form of cap, 8a being a short tube, and 8b its filling plug, which is screwed or fitted tightly into the end of the tube, 6 is the slot to receive the ends of the member 1, 2. The advantage of this form over that shown in Figure 11 is that if any tobacco gets lodged in the slot 6, it can easily be removed by detaching the plug from the tube. Or the collar may be pierced laterally with three or more holes, through which tobacco which may have become lodged in the slot will be ejected when the collar is rotated. In its simplest or most elementary form the device may consist of two half-tubes—the ends of which are preferably bevelled or rounded off—and two removable caps or collars 115 adapted to receive and hold the ends of the half tubes. These caps may be with or without filling plugs, the advantage of the plugs being that they enable a slight longitudinal compression of the charge to be 120 made and a somewhat firmer cigarette to be produced.

What I claim and desire to protect by Letters Patent is:—

1. A cigarette making device comprising 125 two edgewisely separable semi-cylindrical members; each member having at one end a closure guide part provided with a slot adapted to slidably receive the end of the other member to secure the two semi-cylin- 130

drical members adjustably together to form a complete tube closed at both ends.

2. A device for making cigarettes as set forth in claiming clause 1, in which one of the guide parts consists of a short cylindrical block fitted into the end of a half tube and a cylindrical ring or collar surrounding said block, the collar and block and tube being rigidly secured together.

3. A device for making cigarettes consisting of two similar semi-cylindrical members, each having a closing guide part at one of its ends, the open end of one semi-cylindrical member being adapted to pass through the closing member of the other semi-cylindrical member, so that the two assembled semi-cylindrical members forming a complete tube can be reciprocated one upon the other for assembling or disassembling or compressing the filler.

4. A device for making cigarettes as set forth in claim 1 in which the guide part in each half tube fits closely the contour of the end of the complementary half tube when they are assembled together and acts as a support to prevent deformation of the tube when the same is rolled between the fingers to cut off any tobacco protruding from between the meeting edges of the half tubes.

5. A cigarette-making appliance embodying two members each having a body portion semi-cylindrical in cross-section and a

cylindrical closure-device at one end, each closure-device being provided with an opening to slidably receive and guide the semi-cylindrical end of the other member, whereby when the longitudinal edges of the two semi-cylindrical body portions are brought together they form a complete tube 40 and the semi-cylindrical end of each member may be slid into and out of the opening in the closure-device of the other member to thus not only hold the semi-cylindrical body parts together while being rolled in 45 the hands but also to permit the filler to be endwisely compressed before the members are endwisely removed from the paper cigarette wrapper.

6. A cigarette-making appliance embodying two members each of which has a semi-cylindrical body portion and a closure-device at one end having a semi-cylindrical opening adapted to slidably receive the semi-cylindrical end of the other member, these 55 semi-cylindrical ends of the members being each tapered to permit ready insertion into its companion opening, for the purpose set forth.

In testimony whereof I affix my signature 60 in presence of two witnesses.

WILHELM GOERT BOONZAIER.
